ATTORNEY.

UNITED STATES PATENT OFFICE.

CHESTER W. LARNER, OF PHILADELPHIA, PENNSYLVANIA.

PLUNGER-VALVE.

1,373,081.

Specification of Letters Patent. Patented Mar. 29, 1921.

Application filed March 30, 1920. Serial No. 370,001.

To all whom it may concern:

Be it known that I, CHESTER W. LARNER, a citizen of the United States, residing at Philadelphia, in the county of Philadelphia and State of Pennsylvania, have invented 5 certain new and useful Improvements in Plunger-Valves, of which the following is a specification.

Parts of plunger valves used for discharging water at high velocities are subjected to erosion and to the scouring action of the water and, from time to time, have to be renewed. In such cases it is usual to install another or emergency valve ahead of 10 the operating valve used for regulating the flow, so that the water can be cut off from the regulating or operating valve for repairs.

The principal object of the present invention is to combine in one structure a plunger emergency shut-off valve and a plunger operating valve in such a way that the flow can be stopped by the emergency valve and repairs made to the operating valve, thus 15 providing a cheaper and more compact arrangement than is provided by the use of two separate valve structures.

The invention will be claimed at the end hereof, but it may be said to consist in the 20 combination in a unitary separable structure of an operating plunger valve and an emergency shut-off plunger valve substantially as will be described in connection with the accompanying drawing which is an illustration principally in central section.

In the drawings the unitary valve structure comprises detachably connected casings 1 and 2, tapering toward their free ends 3, and provided internally with cylinders 4 and 40 5, and the casings 1 and 2, abut and are separable at the circumferential line 6. Radial ribs 7 and 8, support the cylinders in the casings and provide a water way 9, between the outside surfaces of the cylinders 45 and the inside surfaces of the casings. 10, is a head for one of the cylinders, in the present instance the up-stream cylinder 5. 11 and 12, are reversely disposed hollow plungers coöperating respectively with the tapering ends 3, of the casings, as seats, and arranged in the cylinders 5 and 4, and forming therewith annular chambers 13 and 14, and internal chambers 15 and 16. There are means for closing the up-stream plunger 11, 50 to shut the fluid way 9, and permit of the detachment of the down-stream plunger 12,

and its accessory cylinder 4, and casing 1, at the parting 6. The means shown comprise the valved connection 17, to the annular chamber 13, and to the atmosphere, 60 and the connection 18, to the atmosphere or to pressure as determined by the three-way valve 23. Plunger 12, may be seated, as indicated in dotted lines, or unseated, as indicated in full lines, and plunger 11, may be seated, as indicated by dotted lines, by exhausting chamber 13, to the atmosphere by way of 17, in which case pressure supplied through connection 18, connected to conduit, not shown, up-stream from the valve, or to 70 any suitable source of static pressure equal to or greater than the pressure at the entrance of the casing 2, operates to close plunger 11. Plunger 11, may be opened by exhausting chamber 15, to the atmosphere 75 through connection 18. When plunger 11, is standing open, sometimes 17 and 18, are closed; when plunger 11, is closed connection 17, is open to exhaust and 18 is open to pressure. Plunger 12, may be opened and 80 closed in any of ways known to those skilled in the art; as shown there is provided a port 19, and a port 20, and the port 20, is controlled by a valve 21, operated by valve gear 22, in a manner well understood by those skilled 85 in the art in order to open and close the plunger 12. When this valve gear is used, the head 16, may be dished and pocketed, as shown, to coöperate with it as a guide.

The valve structure is unitary and therefore comparatively inexpensive and very compact and yet it provides an emergency shut-off plunger valve and an operating plunger valve to which and to the parts of which access can be readily had for repairs, 95 while the water is shut off by the emergency plunger valve, by the simple operation of disconnecting the parts at the circumferential parting 6, and after the repairs or removals have been made the parts may be 100 readily reassembled.

Obviously modification may be made in details of construction and arrangement and hence the invention is not limited to those matters or otherwise than as the prior art 105 and the appended claims may require.

I claim:

1. A unitary separable valve structure comprising the combination of detachably connected casings tapering toward their free 110 ends and provided internally with abutting cylinders of which one is headed to inter-

rupt flow through them and of which both provide a water way around them, and reversely disposed hollow plungers coöperating respectively with the tapering ends of 5 the casings and arranged in the cylinders and forming therewith annular and internal chambers, and means for closing the up-stream plunger to shut the fluid way and permit of detachment of the down-stream 10 plunger and its accessory cylinder and casing.

2. A unitary separable valve structure comprising the combination of detachably connected casings tapering toward their free 15 ends and provided internally with abutting cylinders of which one is headed to interrupt flow through them and of which both provide a water way around them, and reversely disposed hollow plungers coöperating 20 respectively with the tapering ends of the casings and arranged in the cylinders, and means for closing the up-stream plunger to shut the fluid way and permit of detachment of the down-stream plunger and its 25 accessory cylinder and casing.

3. A unitary separable valve structure comprising the combination of a pair of detachably connected casings tapering toward their free ends and provided with radial 30 ribs and with abutting internal cylinders providing a water way between the cylinders and the casing and through the structure, a head for separating the inner ends of the cylinders, reversely disposed hollow 35 plungers coöperating with the respective tapering ends of the casings and arranged in the cylinders and forming therewith annular and internal chambers, and means for

closing the up-stream plunger to shut the fluid way and permit of detachment of the 40 down-stream plunger and its accessory cylinder and casing.

4. A unitary separable valve structure comprising the combination of detachably connected casings tapering toward their free 45 ends and equipped internally with abutting cylinders providing a water way around them, reversely disposed hollow plungers coöperating with the tapering ends of the casings and of which the down-stream one is 50 provided with a valve and mechanical valve gear, a head carried by one of the cylinders and accommodating the valve gear, and means for closing the up-stream plunger to shut the fluid way and permit detachment 55 of the down-stream plunger and its accessory cylinder and casing and valve gear.

5. A unitary separable valve structure provided with a water way through it, and of which the sections are provided with reversely disposed plunger valves and their complementary cylinders forming the inner 60 wall of the water way and of which one is headed near the parting of the structure, substantially as described.

6. A unitary separable valve structure having a water way through it and of which the sections are provided with reversely disposed plunger valves, hydraulic means for operating said plunger valves independently of each other, and means for holding the plunger closed against pressure to permit dismantling the down stream section of 65 70 said valve structure.

CHESTER W. LARNER.
